[57] CLAIM

The ornamental design for a seat pedestal, substantially as shown.

DESCRIPTION

FIG. 1 is a side elevational view of the seat pedestal embodying the present design;

FIG. 2 is an elevational view of the seat pedestal shown in FIG. 1, showing the side opposite that seen in FIG. 1; FIG. 3 is a rear elevational view of the seat pedestal seen in FIGS. 1 and 2;

FIG. 4 is a front elevational view of the seat pedestal shown in the preceding figures;

FIG. 5 is a perspective view of the seat pedestal shown in the preceding figures; and

FIG. 6 is a top plan view of the seat pedestal.
